US0D1100225S

(12) **United States Design Patent** (10) **Patent No.:** **US D1,100,225 S**
(45) **Date of Patent:** **** Oct. 28, 2025**

(54) **BUNION CORRECTOR**

(71) Applicant: **Rongxing Jiang**, Wenzhou (CN)

CN 307683382 * 11/2022
CN 307832209 * 2/2023
CN 308267802 * 10/2023

(72) Inventor: **Jinchang Hu**, Wenzhou (CN)

(Continued)

(73) Assignee: **Rongxing Jiang**, Wenzhou (CN)

(**) Term: **15 Years**

(21) Appl. No.: **29/947,115**

(22) Filed: **Jun. 13, 2024**

(30) **Foreign Application Priority Data**

Jan. 20, 2024 (CN) 202430039580.X

(57) **CLAIM**

The ornamental design for a bunion corrector, as shown and described.

DESCRIPTION

FIG. 1 is a front, right and top perspective view of a bunion corrector, showing my new design;

FIG. 2 is a rear, left and bottom perspective view thereof; FIG. 3 is a front, right and top perspective view, shown in condition of use for clarity of disclosure;

FIG. 4 is a front view of the bunion corrector of FIG. 1

FIG. 5 is a rear view thereof;

FIG. 6 is a left side view thereof;

FIG. 7 is a right side view thereof;

FIG. 8 is an enlarged top plan view thereof; and,

FIG. 9 is an enlarged bottom plan view thereof.

The broken lines shown in the drawings illustrate portions of the bunion corrector that form no part of the claimed design.

1 Claim, 9 Drawing Sheets
